UNITED STATES PATENT OFFICE.

CHARLES H. JAMES, OF SPOKANE, WASHINGTON, ASSIGNOR TO UNITED AUTOGRAPHIC REGISTER COMPANY, OF CHICAGO, ILLINOIS, A CORPORATION OF ILLINOIS.

MANIFOLDING DEVICE.

Application filed April 10, 1926. Serial No. 101,135.

My present invention relates to manifolding devices, and has particular reference to a structure wherein a plurality of strips of paper having interleaved carbon sheets are superposed upon a writing bed or plate and the paper strips are withdrawn after such original ticket has been made out by the operator. Such structures are commercially known as autographic registers, and my present invention is directed more specifically to the means for initially projecting the end edge of the paper strips beyond the end of the register structure so as to be readily grasped by the operator and said means are also utilized for the purpose of determining the length of the strips that are withdrawn at each operation. The paper strips are provided with punch-holes or perforations disposed preferably in pairs between the respective tickets that are printed upon the strips and these perforations are utilized by my structure both for initially discharging the end edge of the strips as well as for stopping the withdrawal of the strips at the end of each set of tickets. This is done by providing at the discharge end of the register a pair of pins or stops that engage a set of perforations in the strips and are adapted to be moved towards the discharge end of the register by the operator to project the end of a set of tickets beyond the platen and when the pins or stops are withdrawn from the perforations they automatically return to their normal position while the operator manually pulls out the tickets with the pins or stops contacting the upper surface of the upper strip until the next pair of perforations come into registry with the pins or stops whereupon the latter will move into the same and stop the further movement of the strips. The means that automatically return the pins or stops to normal position also permit the pins to yieldingly move towards the discharge end of the register when they have entered the next set of perforations so as to prevent tearing of the strips due to too sudden stoppage by the pins or stops. This structure has been designed with divers objects in view, among which are compactness in ar-

angement of the parts, dependability in operation, economy in manufacture, and novelty in construction, and I prefer to carry out my invention and accomplish the several objects thereof in substantially the manner hereinafter fully described and as more particularly pointed out in the claims with reference to the accompanying drawings that form a part of this specification.

In the drawings:

Figure 1, is a vertical longitudinal section of a manifolding device or autographic register constructed in accordance with my invention.

Figure 2 is a top plan thereof, drawn to a slightly smaller scale.

Figure 3 is a horizontal section on line 3—3 of Figure 4 of the forward or discharge end of the register and having the marginal frame broken away at the opposite end.

Figure 4 is a transverse vertical section on line 4—4 of Figure 2 and looking in the direction of the arrows.

Figure 5 is an irregular vertical section on line 5—5 of Figure 4.

The drawings are more or less schematic for the purpose of illustrating a typical or preferred embodiment of my invention, and in said drawings I have employed similar reference characters to designate the same parts wherever they appear throughout the several views.

For the purpose of compactness I prefer to employ a rectangular, or box-shaped, housing or casing 10 the top wall of which is preferably omitted and in lieu thereof I provide a writing bed or platen 11 that is preferably hinged at the discharge end of the housing by means of ears 11^a upon transverse pivotal pins 12 secured to the opposite sidewalls of the housing and said platen is supported by elongated cleats or strips 13 secured to the inner surfaces of the opposite side walls of the housing. Thus constructed, the platen may be raised to permit access to the interior of the housing for the purpose of placing therein the supply of paper strips and for threading the same through the register. As shown in Figure 100

1, the strips, three in number, are designated by the numeral 14 and are folded zig-zag back and forth upon themselves in the form of a thick pad 15 that is placed in the bottom of the housing, from which pad the ends of the strips are raised and separated at the rear portion of the platen 11 by passing them over the spaced separators or guide flanges 16. These separators or guide flanges 10 are formed by giving the end of the platen a reverse bend downwardly, and by cutting transverse parallel slots 17 in the adjacent portion of the platen and turning the slotted portions down and under in the manner 15 shown so that the slots 17 will permit of the free passage of the strips.

After passing through the slots and over the end of the platen the strips are led across the platen to the discharge end thereof and 20 in order to maintain the strips flat upon the platen a marginal frame 18 is provided that has depending longitudinal flanges 19 upon its side edges that fit over the upper portions of the side walls of the housing and provide 25 means for hinging the marginal frame upon the pivot pins 12 that hingedly mount the platen on the housing. The end edge of the marginal frame at the discharge end of the register may be sharpened to provide a 30 tearing or cutting edge 20 against which the tickets are torn from the strips after being pulled out, and adjacent this edge the marginal frame is provided with longitudinally disposed elongated slots 21, 21, that are im- 35 mediately above and in alinement or registration with longitudinally disposed elongated slots 22, 22, in the platen, and said marginal frame and platen are preferably separated from each other a slight distance 40 vertically so as to provide a passageway between the same for the strips.

An elongated hood 23 is secured to the marginal frame at the discharge end of the register above the slots 21, which hood en- 45 closes the devices that are utilized to control the movement of the strips. Extending between the longitudinal vertical walls of the hood is a tubular guide 24 the ends of which are secured to the walls midway 50 between the ends of the latter. A recipro- cable slide or carrier 25 is mounted upon the guide so that it may move to and fro with respect to the end of the register and in a direction longitudinally of the platen. 55 This slide or carrier is automatically return- able and its normal position is adjacent the rear wall of the hood as illustrated in the drawings, and in order to yieldably main- tain the slide or carrier in this position 1 60 insert a coiled expansion spring 26 within the guide prior to assembly, which spring is engaged by a stop-pin 27 that passes through the slide and through oppositely disposed elongated slots 28 made longitudinally in the guide. The opposite ends of

the slide or carrier are bifurcated to pro- vide spaced ears 29 between which bell- cranks are pivotally mounted upon hinged pins 30. The up-standing arms of the bell- cranks in the form of finger grasps 31, 31 70 pass through elongated slots 32, 32 in the top wall of the hood and afford means for rocking the bell-cranks as well as means for the operator to grasp to slide the carrier to- wards the discharge end of the register when 75 it is desired to initially discharge the strips as will be hereinafter described. The other arms of the bell-cranks are preferably in the form of flat bars or levers 33, 33, that extend in opposite directions from the piv- ots 30 towards and over the slots 21 in the margin frame, and upon their outer end portions have depending elements in the form of pins or stops 34, 34, that project downwardly through said slots and also 80 through the slots 24 in the platen. The paper strips are provided with punch-holes or perforations 14^a arranged in pairs be- 85 tween the tickets and are spaced apart trans- versely of the strips the distance between the pins or stops 34 so that the latter will enter said perforations when the strips are in registry with each other and with said pins or stops.

The levers or bars 33 of the bell-cranks are 90 maintained yieldingly in their normal posi- tions, preferably against the surface of the margin frame 18 and with the pins or stops urged towards the strips or through the per- forations 14^a by means of leaf springs 35 100 that are anchored at one end on the lever bars 33 and extend obliquely towards and engage the top wall of the hood.

When the strips have been properly as- 105 sembled and led through the register and the pins or stops 34 are engaged in the strips perforations 14^a the device is ready to be operated. After writing the ticket, the operator moves the handles 31 of the bell- cranks away from him to their full limit 110 of movement towards the discharge end of the register and against the action of spring 26, which will project the ends of the tickets beyond the cutting edge 20 a distance sufficient to be grasped by the fingers of the operator. The handles 31 are then moved 115 towards each other by the operator, which will rock the bell-cranks and withdraw the pins or stops 34 from the strip perforations, and when the handles are released the slide or carrier is automatically returned to its 120 normal position by the spring 26. At the same time the springs 35 urge the pins or stops 34 into engagement with the strips back of the perforations from which the pins or stops have just been withdrawn and will press against the perforated portion of the strips. The operator pulls out the strips 125 and in so doing moves the next pair of per- forations into position below the pins or 130

stops so that they will enter the same and stop further withdrawal of the strips. If the operator exerts too much force in extracting the strips after the pins or stops 5 have entered the new set of perforations the slide or carrier, and the parts mounted thereon, will be moved forward a slight distance against the tension of the coiled spring 26 within the guide thus preventing 10 the tearing of the strips, and as soon as the pull is released the carrier will automatically return to normal position moving the strips back with it. After the pull out has been stopped the ticket may be severed by 15 pulling the strips upwardly against the blade 20, and thereafter the structure is ready for the next operation.

Obviously other instrumentalities may be devised for carrying out the principles of 20 my invention, and I therefore desire it understood that such changes and modifications are fully contemplated as coming within the scope of the appended claims.

What I claim is:—

1. A manifolding device comprising a platen across which perforated strips are adapted to be moved, said platen having longitudinal slots in alinement with the strip perforations, an automatically returnable 30 carrier reciprocally mounted above said platen, yieldable arms mounted on and bodily movable with said carrier, and means on said arms adapted to enter the strip perforations and the slots in said platen and project the ends of the strips beyond the end of the platen.

2. A manifolding device comprising a longitudinally slotted platen across which perforated strips are adapted to be moved with 40 the perforations in alinement with the slots, an automatically returnable carrier reciprocably mounted above said platen between said slots, and yieldable arms on said carrier that are bodily movable therewith and are provided with means adapted to enter the strip perforations and the slots in the platen and project the ends of the strips beyond the end of the platen when the carrier is moved towards the end of the platen.

3. A manifolding device comprising a longitudinally slotted platen across which perforated strips are adapted to be moved with the perforations in alinement with the slots, an automatically returnable carrier reciprocably mounted above said platen between said slots, and automatically returnable bell-cranks pivoted on and bodily movable with said carrier the horizontal arms of which extend in opposite directions past the slots in the platen and are provided with means that enter said slots and the strip perforations whereby the movement of the carrier towards the discharge end of the platen will project the ends of the strips beyond the platen.

4. A manifolding device comprising a slotted platen across which perforated strips are adapted to be moved with the perforations in alinement with said slots, and arms pivoted to move up and down transverse to the platen and normally yieldingly urged towards the platen and provided with means that enter the slots and perforations, said arms adapted to be bodily moved towards the end of the platen while engaged in the strip perforations whereby to project the ends of the strips beyond the platen.

5. A manifolding device comprising a slotted platen across which perforated strips are adapted to be moved with the perforations in alinement with said slots, arms pivoted to move up and down transverse to the platen and normally yieldingly urged towards the platen and provided with means to engage the strips through the perforations, and means movable longitudinally of the platen upon which said arms are mounted whereby to bodily move said arms towards the end of the platen and thereby project the strips beyond the platen.

6. A manifolding device comprising a slotted platen across which perforated strips are adapted to be moved with the perforations in alinement with said slots, oppositely extending hinged arms yieldingly urged towards the platen and provided with means adapted to enter the strip perforations, and automatically returnable means movable towards the discharge end of the platen and upon which said arms are pivoted, whereby to move the end of the strips beyond the end of the platen.

7. A manifolding device comprising a platen across which perforated strips are adapted to be moved, and means for intermittently moving the strips through the medium of the perforations therein comprising automatically returnable arms pivoted to move in a plane transverse to the plane of movement of the strips and having stops to enter the strip perforations, and an automatically returnable carrier upon which said arms are mounted, which carrier being movable longitudinally of the platen both toward and away from the discharge end thereof.

8. A manifolding device comprising a platen across which perforated strips are adapted to be moved, and means for controlling the movement of the strips through the medium of the perforation therein, said means including movable arms extending transversely of the strips and having stops thereon, said means being movable with respect to the strips in planes intersecting each other, the movement in one direction adapted to discharge a portion of the length of the strips and the movement in the other direction adapted to arrest the movement of the strips.

9. A manifolding device comprising a platen across which perforated strips are adapted to be moved, and stops for controlling the movement of the strips through the medium of the perforations therein which stops are movable longitudinally of the platen to feed said strips a predetermined distance for subsequent withdrawal and also movable transverse to the strips to arrest the withdrawal of the strips. 10

Signed at Spokane, in the county of Spokane, and State of Washington, this 3rd day of April, 1926.

CHARLES H. JAMES
